UNITED STATES PATENT OFFICE.

DAVID T. MAY, OF NEW YORK, N. Y., ASSIGNOR TO WESTERN ELECTRIC COMPANY, OF NEW YORK, N. Y., A CORPORATION OF ILLINOIS.

FLEXIBLE CONDUCTOR.

1,116,090.

Specification of Letters Patent.

Patented Nov. 3, 1914.

Application filed April 27, 1912. Serial No. 693,633.

To all whom it may concern:

Be it known that I, DAVID T. MAY, citizen of the United States, residing at New York, in the county of New York and State of New York, have invented a certain new and useful Improvement in Flexible Conductors, of which the following is a full, clear, concise, and exact description.

This invention relates to flexible conductors, and particularly to flexible conductors for use in making telephone switchboard cords.

An object of this invention is the production of a cord which will have all the advantages of the tinsel cord of ordinary type as regards flexibility, and all the advantages of the steel cord as regards durability without any of the disadvantages common to either.

This invention covers a conductor in which individual twists composing a strand are so laid together that the tape of each twist is tightened on the thread in the process of making the strand, and the strands are twisted together into a rope which has no central core, the whole construction resulting in a conductor of high efficiency.

In the drawing, the figure shows a section of cord constructed in accordance with my invention, the end being broken away to show the method of construction employed.

A thread 10, having a tape 11 of conducting material wound thereon, forms a twist or a tinsel thread 9. A plurality of twists 9 are laid together, in a close spiral, with a right-hand lay; that is, in such a way that the tape 11 of each twist 9 is tightened on the thread 10 thereof. The laying together of the twists 9 results in a strand 12. Three strands 12 are then laid directly together with a left-hand lay to form a conductor 8. In the completed conductor 8 the relation between the length of lay (that is, the linear advance in making a complete turn) in each strand and the length of lay in the whole conductor is such that there is no tendency for the conductor to kink or untwist. The conductor resulting from the laying together of the strands 12 is then wrapped with two servings of insulation 13 and 14 wound tightly on the conductor in opposite directions, after which a braiding of cotton

or silk 15 is placed thereon, as is usual. Three of these conductors are then taken and twisted together in the form of a rope without any core being used; and after twisting, threads of ordinary cotton 16, 17 and 18, are used for the purpose of making a smooth finish on the outside of the cord.

In twisting the three insulated conductors together, no attempt is made to form them to prevent separation of the conductors as the resulting core is wrapped with a spaced serving of cotton 19, which accomplishes the same purpose. Over the resulting core is then braided a covering of glazed cotton 20, or other suitable material.

What is claimed is:

1. In a flexible conductor, a plurality of twists each comprising a thread and a conducting tape wound thereon, said twists forming a strand laid together in a direction to tighten the tape on each individual thread, and a plurality of such strands laid together in a direction opposite to that of each strand, the relation between the length of lay in each strand and the length of lay in the whole conductor being such that there is no tendency for the conductor to kink or untwist.

2. In a flexible conductor, a plurality of twists, each comprising a thread and a conducting tape wound thereon, said twists forming a strand laid together in a close spiral and in a direction to tighten the tape of each twist, and a plurality of such strands laid directly together in a close spiral and in a direction opposite to that of said twists, the relation between the length of lay in each strand and the length of lay in the whole conductor being such that there is no tendency for the conductor to kink or untwist.

3. The method of making a flexible conductor, which consists in winding a conducting tape about a thread thereby forming a twist, laying together a plurality of such twists in a direction to tighten the tape of each twist thereby forming a strand, and laying together a plurality of such strands in a direction opposite to that of the twists.

4. The method of making a flexible conductor, which consists in winding a conducting tape about a thread thereby form-

ing a twist, laying together a plurality of such twists in a direction to tighten the tape on each twist thereby forming a strand, and laying a plurality of such strands directly together in a close spiral and in a direction opposite to that of the twists and with such a relation between the length of lay in each strand and the length of lay in

the whole conductor that there is no tendency for the conductor to kink or untwist. ¹⁰

In witness whereof, I hereunto subscribe my name this 25th day of April A. D., 1912.

DAVID T. MAY.
